His Attorney.

UNITED STATES PATENT OFFICE

WALTER R. G. BAKER, OF SCHENECTADY, NEW YORK, ASSIGNOR TO GENERAL ELECTRIC COMPANY, A CORPORATION OF NEW YORK

CARRIER-CURRENT SYSTEM

Application filed April 24, 1925. Serial No. 25,644.

My present invention relates to signaling systems, and more particularly to signaling systems of the carrier current type in which high frequency signaling currents are conducted over wires.

In many carrier current installations the various circuits radiating from the power house or switching station are not metallically connected. While it might in general be thought desirable to connect all coupling conductors together and then run the lead-in wire direct to the carrier equipment, this method has the distinct disadvantage that the entire system must always be charged by the carrier current.

It is an object of my invention to provide a carrier current system having a selectively controlled indicating device normally connected to each line of the system, and selectively controlled communication apparatus normally disconnected from each line of the system. With this arrangement, when a call is indicated on any one line of the system, the communication apparatus may be connected to that one line alone. At the same time the indicating device may be disconnected from the line over which the call has been transmitted, but will remain connected to the other lines of the system. In this manner several stations are permitted to call at the same time giving an arrangement which is particularly desirable when the system is extended to cover inter-system work.

The novel features which I believe to be characteristic of my invention are set forth with particularity in the appended claims. My invention itself, however, both as to its organization and method of operation will best be understood by reference to the following disclosure taken in connection with the accompanying drawing, in which the figure shows a circuit organization whereby my invention may be carried into effect.

Referring to the drawing I have indicated at 1, 2 and 3 a plurality of coupling conductors adapted to be associated with a corresponding number of wires of a system of distribution not shown. The carrier communication apparatus including a duplex carrier transmitter 4, a duplex carrier receiver 5,

and a telephone 38, is normally disconnected from the system, but is adapted to be selectively connected to the coupling conductors by means of switches 6, 7 and 8. The switches are operated by means of a plurality of solenoids 9, 10 and 11, supplied by a common source of energy 12, and controlled by switches or keys 13, 14 and 15 respectively.

The calling apparatus comprises a selector notching relay 16, which may, for example, be of the type described in Patent No. 865,536 Scribner and Enochs 1907, and an indicating drop and bell arrangement 17 normally connected to conductors 1, 2 and 3 by means of a plurality of switches 18, 19 and 20. The latter switches are operated by a plurality of solenoids 21, 22 and 23, supplied from a common source of energy 24, and selectively controlled by a plurality of switches 25, 26 and 27.

The indicating device 17 comprises a plurality of switches 28, 29 and 30 in circuit with a plurality of solenoids 31, 32 and 33 respectively. The solenoids are supplied from a source of energy 34 and control the operation of indicating drops and bells 35, 36 and 37.

The operation of the device is as follows:— When a call comes in over the coupling conductor 1 the impulses pass through switch 18 and the winding of selector relay 16. The selector relay is notched up to a point where contact 28 is closed, operating in this manner the indicating bell and drop 35. The operator noting that the indicator 35 has been operated depresses the key or switch 25 energizing solenoid 21 to open switch 18 and deenergize the selector relay. At the same time the operator depresses the key or switch 15 thereby energizing coil 9 and closing switch 6 to connect the communication apparatus to the coupling conductor.

If the local station wishes to send out a call over coupling conductor 1 the operator depresses key 15 which closes a circuit through coil 9 to operate switch 6. The duplex carrier and receiver are then connected to the coupling conductor. At the time key 15 is depressed key 25 may be operated to

open contact 18 to disconnect the indicating device from coupling conductor 1.

While separate keys are shown energizing the two coils associated with any one coupling conductor, obviously both coils may be arranged to be operated by one key only if desired. For example, coils 9 and 21 might be connected either in series or in parallel so that when key 15 is depressed switch 6

10 will be closed and switch 18 opened.

When any one line is in operation the signaling system will, of course, be disconnected from that one line. The other lines remain connected to the signaling system so 15 that calls may be indicated on any line except the line which is at that time in operation.

By the term "coupling conductor" I mean any conductor which may be employed to 20 electrostatically connect carrier equipment to a system of distribution, or the like. While I have shown coupling wires adapted to connect the carrier equipment to a system of distribution, obviously, coupling condensers 25 may be employed instead if desired. Each conductor 1, 2 and 3 would then be connected to one of the plates of a coupling condenser while the other plates of the condensers would be connected to the system of distribution.

While I have shown a carrier system operated from phase to ground, it is, of course, obvious that the system will operate equally well interphase employing either coupling 35 condensers, or coupling conductors as shown. Various modifications of my device will readily suggest themselves to persons skilled in the art without departing from the scope of my invention as set forth in the appended 40 claims.

What I claim as new and desire to secure by Letters Patent of the United States is:

1. A carrier current signaling system comprising a plurality of coupling conductors, 45 communication apparatus normally disconnected from said conductors, a plurality of indicating devices, each indicating device corresponding to one of said coupling conductors, a single means normally connected to all of said conductors for selectively actuating said indicating devices, and means for connecting the communication apparatus to one of said conductors and for disconnecting said single selective actuating means from 50 that conductor only.

2. A carrier current signaling system comprising a plurality of coupling conductors, communication apparatus normally disconnected from said conductors, a plurality of 55 indicating devices, each indicating device corresponding to one of said conductors, a single means normally connected to all of said conductors for selectively actuating said indicating devices and means for selectively connecting said communication apparatus to

any one of said conductors and for disconnecting said single selective actuating means from that conductor.

3. A carrier current signaling system comprising a plurality of coupling conductors, 70 communication apparatus normally disconnected from said conductors, a plurality of indicating devices, each indicating device corresponding to one of said coupling conductors, a single means normally connected to all of said conductors for selectively actuating said indicating devices, means for selectively connecting said communication apparatus to said conductors and means for selectively disconnecting said single selective 75 actuating means from any one of said conductors.

4. A carrier current signaling system comprising a plurality of coupling conductors, communication apparatus normally disconnected from said conductors, a plurality of indicating devices, each indicating device corresponding to one of said coupling conductors, a single means normally connected to all of said conductors for selectively actuating said indicating devices, means for selectively connecting said communication apparatus to any one of said conductors and for maintaining said communicating apparatus disconnected from the remaining conductors, and means for disconnecting said single selective actuating means from said one conductor and for maintaining said single means connected to the remaining conductors.

5. A carrier current signaling system comprising a plurality of coupling conductors, communication apparatus normally disconnected from said conductors, a plurality of indicating devices, each device corresponding to one of said coupling conductors, a single means normally connected to all of said conductors for selectively actuating said indicating devices, and means for selectively connecting said communication apparatus to any one of said conductors and for disconnecting said single selective actuating means from said one conductor only.

In witness whereof, I have hereunto set my hand this 23d day of April, 1925.
